UNITED STATES PATENT OFFICE.

DOMINIC A. VALVANO, OF LINDEN, NEW JERSEY.

CHECK-REGISTEE.

1,263,966.

Specification of Letters Patent. Patented Apr. 23, 1918.

Application filed November 16, 1917. Serial No. 202,390.

To all whom it may concern:

Be it known that I, DOMINIC A. VALVANO, a subject of the King of Italy, and a resident of Linden, in the county of Union and State of New Jersey, have invented a new and Improved Check-Register, of which the following is a full, clear, and exact description.

This invention relates to registers and particularly to a check register for use in barber 10 shops and other places and has for an object the provision of an improved construction which will show at all times the value of the checks removed.

Another object in view is to provide a 15 register for each barber in a barber shop or other place arranged with different columns of checks with indications alongside the columns showing the value of the checks removed automatically.

20 In the accompanying drawing:

Figure 1 is a front view of a register disclosing an embodiment of the invention.

Fig. 2 is a section through Fig. 1 on line 2—2.

25 Referring to the accompanying drawing by numerals, 1 indicates a base formed of any desired material and 2 a body formed of any desired material, as for instance wood, said body being provided with a plurality of 30 bores 3, certain of said bores being divided by a division plate 4, which thereby produces a plurality of upper sections 5 and a plurality of lower sections 6. The upper sections 5 and the bore 3 extend for the full height of 35 the body 2 and are open at the top, while the sections 6 are closed at the top, but are provided with notches 7 and 8 adjacent the top through which the various checks 9 may be passed inwardly or outwardly. After a few 40 checks have been used the upper check may be grasped by the person using the device and turned edgewise so as to quickly remove the same. Arranged alongside of each bore

3 including sections 5 and 6 are numbers 10 indicating the values whereby after a number 45 of coins have been removed from the bore the value of the removed coins can be instantly observed. For instance, under the section 5 indicating twenty five cent checks it will be seen that a sufficient number of checks have 50 been removed to produce one dollar and twenty five cents. Under the column thirty five will be seen three dollars and fifteen cents worth of checks have been removed. When the device is in use in a barber shop 55 or otherwise, the barber will remove a check and hand to the customer who will pay at the cashier's desk and by the removal of the check the barber automatically registers the value of the work done so that at the end 60 of the day he may add up the values of the various columns and find out the total of the work done. It will be noted that the various checks 9 are of such a thickness as to always come opposite the respective numbers 65 regardless of the value of the check, as said checks are preferably of the same size and thickness though the indicated values are different.

What I claim is:

70 A register of the character described comprising a plurality of sockets, each of said sockets having a slot in one side, a plurality of numbers arranged alongside each of said slots, a fixed division member arranged in 75 said body and dividing certain of said sockets into upper and lower sections, said body also being provided with notches for the lower section, said notches being arranged adjacent said division plate, and a plurality 80 of checks for each of said sockets, said checks being of such a thickness as to appear opposite said numbers, and the said notches being of such a size as to permit the checks to be moved therethrough.

DOMINIC A. VALVANO.
